ALEXANDER BECK, OF PHILADELPHIA, PENNSYLVANIA.

Design No. 2,617, dated April 16, 1867.

DESIGN FOR A CARPET PATTERN.

The Schedule referred to in these Letters Patent and making part of the same.

TO ALL WHOM IT MAY CONCERN:

Be it known that I, ALEXANDER BECK, of Philadelphia, county of Philadelphia, State of Pennsylvania, have invented or produced a new and original Design for a Carpet Pattern; and I do hereby declare that the accompanying drawing, and the following explanation thereof, form a full, clear, and exact description of the said design.

In the drawing, Figure 1 represents one-half of a strip of a hall or stair carpet, and Figure 2 the same with sundry dark parts removed for the better illustration of the pattern. The line A represents the outer edge of the carpet, and the line B the middle of the same, longitudinal striped ornaments, clearly illustrated in the drawing, extending throughout the entire length of the piece.

I claim the design for a carpet pattern, substantially as represented in and by the accompanying drawing. In testimony whereof I have signed my name to this specification in the presence of two subscribing witnesses.

ALEXANDER BECK.
